UNITED STATES PATENT OFFICE.

MARY E. CAMERON, OF ALBANY, NEW YORK.

DESIGN FOR A GAME-BOARD.

SPECIFICATION forming part of Design No. 21,880, dated October 4, 1892.

Application filed August 3, 1892. Serial No. 442,069. Term of patent 3½ years.

To all whom it may concern:

Be it known that I, MARY E. CAMERON, a citizen of the United States, residing at the city and county of Albany, State of New York, 5 have invented a new and original Design for a Parlor Game-Board, of which the following is a specification, reference being had to the accompanying drawing, forming part thereof.

I usually construct my board in the form of 10 an oblong, having the corners at one end rounding, squared at the other, and place around the edge of the board an upwardly-projecting border-piece *a*, as shown in the drawing, which is a plan of my invention.

15 Near one end of the board and about midway between its lateral sides I produce an elongated oval-shaped figure, which elongated oval is divided by a line near each end thereof, forming at each end a figure having a right line for one side and the other side a curve concaved toward said right line. There is a 20 series of nine squares between the said right lines and the lateral sides of the elongated oval.

Centrally on the board and near the lower 25 end thereof is a short line extending partly across the board, and in the lower right and left hand corners opposite the said line are two rectangular panels.

It will thus be seen that the leading features of my design are the rectangular board with corners rounded slightly at the upper end thereof and having the raised margin on its end provided with the elliptical figure in the upper field with the series of squares 35 located centrally therein and having a rectangular panel in each of the lower corners.

What I claim as my invention, and desire to secure by Letters Patent, is—

The design for a game-board, substantially 40 as herein shown and described.

MARY E. CAMERON.
